UNITED STATES PATENT OFFICE

EUGENE H. BALLOU, OF PAWTUCKET, RHODE ISLAND, ASSIGNOR TO DRAPER COMPANY,
OF HOPEDALE, MASSACHUSETTS, A CORPORATION OF MAINE.

THREAD-CUTTER FOR THE DEPLETED WEFT OF WEFT-REPLENISHING LOOMS.

1,138,272.

Specification of Letters Patent.

Patented May 4, 1915.

Application filed October 18, 1912. Serial No. 726,477.

To all whom it may concern:

Be it known that I, EUGENE H. BALLOU, of Pawtucket, in the county of Providence and State of Rhode Island, have invented 5 certain new and useful Improvements in Thread-Cutters for the Depleted Weft of Weft-Replenishing Looms, of which the following is a specification.

In so-called "feeler" weft-replenishing 10 looms wherein the replenishment is effected prior to the complete exhaustion of the running weft, the spent depleted weft-carrier is ejected from the loom while still retaining some weft, with the result that a weft thread 15 is left extending from the selvage through the eye of the shuttle to the discharged depleted weft-carrier. It is important that this depleted weft thread should be promptly severed before the first flight of 20 the shuttle with the fresh supply of weft.

The present invention consists in an improved thread cutter which promptly and certainly cuts this weft thread of the depleted weft-carrier.

25 The present improvements are illustrated in the accompanying drawings, wherein—

Figure 1, is a side view of enough of a loom equipped with the present improvements to enable the improvements to be understood, the lay at the replenishing side of 30 the loom being shown in vertical section in the plane indicated by the line 1—1 in Fig. 2. Fig. 2, is a plan view of the pertinent portions of the loom, a part of the lay being 35 shown in horizontal section. Fig. 3, is a vertical longitudinal section of a portion of the lay at the replenishing side of the loom in the plane indicated by the line 3—3 in Fig. 2. Figs. 4, and 5, illustrate the 40 thread cutter and the thread cutter in different operative positions, the lay in each figure being illustrated in vertical transverse section in the plane indicated by the line 4—4 in Fig. 2.

45 The present improvements are illustrated in the accompanying drawings in connection with weft-replenishing mechanism of the character set forth in Letters Patent of the United States No. 1,082,390, December 23, 50 1913. In accordance with that patent the lay A, carries a spare weft-carrier B, (Fig. 1) immediately above the shuttle-box C, at the replenishing side of the loom and, when weft-replenishment is called for, the 55 shuttle-box is lifted, with the result that the spare weft-carrier held on the lay is trans-

ferred to the shuttle and the depleted weft-carrier is ejected. At a subsequent beat of the lay a fresh weft-carrier is transferred from a magazine independent of the lay to 60 the lay, ready for the next call for replenishment. In accordance with that patent, when the change-shaft D, of the loom is rocked as the result of the detecting action of a weft-detector, a train of mechanism is 65 put into action which results in the lifting of the shuttle-box.

In accordance with the improvements of the present application, the thread cutter E, is actuated at the proper instant by appropriate instrumentalities operatively connected with the train of mechanism intervening between the change-shaft D, and the shuttle-box C, and the thread of the depleted weft-carrier is moved into the jaws of the cutter 75 by means of a thread director F, which is moved as the immediate result of the lifting of the shuttle-box C.

Accordingly, the connecting train of mechanism between the change-shaft D, and 80 the shuttle-box C, is illustrated in the accompanying drawings so that the movements of the thread cutter E, and the thread-director F, may be understood.

The change-shaft D, has a crank arm 10, 85 fast thereon which, at its inner end, is connected by a link 11, with a crank arm 12, on a rock-shaft 13. This rock-shaft 13, at its rear end has an actuator 14, which engages a grooved collar 15 (see Fig. 2) on a spindle 16, which slides in a sleeve 17, on the rear end of a lifting lever 18, which is pivoted at 19 to the loom frame. At its outer end this sliding spindle 16, carries a cam-roll 20, which co-operates with a cam 21, on the low or cam-shaft G, of the loom. Normally the cam-roll 20, is out of the path of the cam 21, as shown in Fig. 2, being maintained in this idle position by the spring 22. When, however, the change-shaft 100 D, is rocked as the result of the approaching exhaustion of the weft, the cam-roll 20, is moved outwardly into the path of the cam 21, thereby rocking the lifting-lever 18. This lifting-lever 18, at its forward end is 105 connected by an ordinary "give-way" connection 23, and a rod 24, to a lifting-rod 25, and this lifting-rod 25, is connected in a well-known way to the rising and falling shuttle-box C. Hence when the cam-roll 110 20, is in the path of the cam 21, the shuttle-box is lifted. After the cam 21 passes the

cam-roll 20, a spring 26, restores the shuttle-box C, to its normal low position; and the spring 22, restores the cam-roll 20, to its normal idle position.

5 The cutter E, has a stationary jaw a, and a pivoted jaw b. The stationary jaw a, is carried by a slide H, mounted to slide on the breast-beam I, and normally held in its rearward position by a spring J. The pivoted 10 jaw b, at its forward end is connected by a link c, with a crank-arm d, on the inner end of a rock-shaft e. At the outer end of the rock-shaft e, is a second crank-arm f, to which is adjustably connected the upper end 15 of a rod g, which, at its lower end, passes through an aperture in an arm h, rigidly fastened to the front portion of the link lever 18. The rod g, is yieldingly connected 20 with the arm h, by means of a spring i, which bears at its lower end upon the arm h, and at its outer end against a collar j, fast 25 on the rod g. Nuts l, adjustably screwed to the lower end of the rod g, beneath the arm h, maintain the rod g, in proper relation to the arm h. It is evident that when 30 the forward end of the lifting lever 18, is raised for the purpose of lifting the shuttle-box (and hence getting a fresh weft-carrier) the rods g, and c, are likewise lifted, thereby 35 causing the jaw b, to swing downwardly past the jaw a, thereby severing any thread which may then be between the jaws. The timing of the change-shaft D, is such that it rocks when the shuttle containing the 40 depleted weft-carrier is in the shuttle-box C, at the replenishing side of the loom, in accordance with the usual timing in weft-replenishing looms. Therefore the thread extending from the selvage at the replenishing 45 side of the loom to the nearly depleted weft-carrier within the shuttle K, extends behind the jaws.

This strand of weft is guided and directed to and between the jaws before the pivoted 50 jaw closes by means of the thread director F. This thread director F, as best shown in Fig. 3, is an arm depending from a horizontal rock-shaft L, carried by the lay near the entrance to the shuttle-box C. The 55 thread-director F, ordinarily is located behind the reed M, as shown in Fig. 4, with its lower free end immediately above the plane of the race-plate N, of the lay. The upper surface of the lay is recessed at m, to permit the forward swing of the lower hooked end n, of the thread-director F. Accordingly, when the director F, is swung 60 forwardly, its lower hooked end travels forwardly in the lay recess m, first below the plane of the weft-thread, thereby taking hold of the weft-thread and then carrying it forward and above said recess and between the jaws of the cutter, as shown in Fig. 5. This thread-directing movement of 65 the thread-director F, occurs before the

pivoted jaw b closes, so that the thread is certainly cut.

This forward swing movement of the thread-director is effected by the rise of the shuttle-box C. The thread-director F, is 70 at the inner end of the shaft L, as shown in Fig. 3, and at its outer end said shaft L, has a crank-arm o, (Figs. 2 and 3) which is immediately above a tappet P, (Fig. 3) secured to the top of the shuttle-box C. Accordingly, when the shuttle-box rises, the thread-director F, is swung forward carrying the thread between the still open jaws of the cutter E. The pivoted cutting jaw b, begins to close substantially as soon as the 75 thread-director F, begins its forward swing, but the thread-director F, is given sufficient surplus swing, as indicated in Fig. 5, so that it can carry the thread between the jaws while they are still apart and before the 80 pivoted jaw b, closes down.

The thread-cutter is located above the plane of the lay so that the lay passes beneath the cutter, and the thread director on the lay directs the thread into the path of 90 the cutter while the shuttle with the depleted weft which is to be cut is in the neighboring shuttle box.

The surplus swing of the thread director F carries it forward of the cutting jaws, as 95 shown in Fig. 5. As the thread at this time extends from the selvage of the cloth to the shuttle, this extent of swing of the thread director tightens the thread so that it is held taut when the cutter acts, thus insuring the 100 cutting of the thread.

As the shuttle-box descends a torsional spring Q, restores the thread-director to its 105 normal rearward position of rest, and the pivoted jaw of the cutter opens.

A spring J, permits the entire cutter to slide forward in case of any obstruction as, for example, in case the shuttle fails to properly box in the shuttle-box C.

I claim—

1. A weft-replenishing loom wherein the replenishment occurs prior to the complete exhaustion of the running weft having, in combination, a rising and falling shuttle-box at the replenishing side of the loom; a 115 change-shaft which is rocked when the running weft approaches exhaustion; a train of mechanism operatively located between the change-shaft and the shuttle-box, whereby the shuttle-box is lifted for the purpose 120 of obtaining a fresh supply of weft and for, ejection of the depleted weft-carrier; a 125 pivoted-jaw; instrumentalities between said pivoted-jaw and the train of mechanism which lifts the shuttle-box, whereby the pivoted-jaw is closed upon the stationary jaw concurrently with the lifting of the shuttle-box; the lay having a recess below the race-way of the lay; a thread-director 130

normally located back of the reed and having a hook at its lower end which swings forwardly first through and then above and in front of said recess when the thread-director is actuated; a rock-shaft carried by the lay which carries said thread-director, said rock-shaft having a crank-arm; and a tappet on the rising and falling shuttle-box which encounters said crank arm when the shuttle-box rises, whereby the thread-director is swung forward to catch the weft and deliver it between the jaws of the cutter.

2. A weft-replenishing loom wherein the replenishment occurs prior to the complete exhaustion of the running weft having, in combination, a rising and falling shuttle-box at the replenishing side of the loom; a change-shaft which is rocked when the running weft approaches exhaustion; a train of mechanism operatively located between the change-shaft and the shuttle-box, whereby the shuttle-box is lifted for the purpose of obtaining a fresh supply of weft and for ejection of the depleted weft-carrier; a thread-cutter having a stationary jaw and a pivoted jaw; instrumentalities between said pivoted jaw and the train of mechanism which lifts the shuttle-box, whereby the pivoted jaw is closed upon the stationary jaw concurrently with the lifting of the shuttle-box; the lay having a recess below the race-way of the lay; a thread-director normally located back of the reed and having a hook at its lower end which moves forwardly through said recess when the thread-director is actuated; and actuating devices between the thread-director and the rising and falling shuttle-box which actuate the thread-director when the shuttle-box rises, whereby the thread-director is moved forward to catch the weft and deliver it between the jaws of the cutter.

3. A weft-replenishing loom wherein the replenishment occurs prior to the complete exhaustion of the running weft having, in combination, a shuttle-box movable upon the lay at the replenishing side of the loom; a weft-detector controlled train of mechanism which moves the shuttle-box with respect to the lay for the purpose of obtaining a fresh supply of weft and for ejection of the depleted weft-carrier; a thread-cutter; instrumentalities between said thread-cutter and the train of mechanism which moves the shuttle-box, whereby the cutter acts concurrently with the lifting of the shuttle-box; the lay having a recess below the race-way of the lay; a thread-director normally located back of the reed and having a hook at its lower end which moves forwardly through said recess when the thread-director is actuated; and actuating devices between the thread-director and the shuttle-

box which actuate the thread-director when the shuttle-box moves, whereby the thread-director is moved forward to catch the weft and deliver it to the cutter.

4. A weft-replenishing loom wherein the replenishment occurs prior to the complete exhaustion of the running weft having, in combination, a shuttle-box movable upon the lay at the replenishing side of the loom; a weft-detector controlled mechanism which moves the shuttle-box upon the lay for the purpose of obtaining a fresh supply of weft and for ejection of the depleted weft-carrier; a thread-cutter; the lay having a recess below the race-way of the lay; a thread-director normally located back of the reed and having a hook at its lower end which moves forwardly through said recess when the thread-director is actuated; and actuating devices between the thread-director and the shuttle-box which actuate the thread-director when the shuttle-box moves, whereby the thread-director is moved forward to catch the weft and deliver it to the cutter.

5. A weft-replenishing loom wherein the replenishment occurs prior to the complete exhaustion of the running weft having, in combination, a shuttle-box movable upon the lay at the replenishing side of the loom; weft-detector controlled mechanism which moves the shuttle-box upon the lay for the purpose of obtaining a fresh supply of weft and for ejection of the depleted weft-carrier; a thread-cutter; a thread-director normally located back of the reed; and actuating devices between said thread-director and the shuttle-box which actuate the thread-director when the shuttle-box moves, whereby the thread-director is moved forward to catch the weft and deliver it to the cutter.

6. A weft-replenishing loom wherein the replenishment occurs prior to the complete exhaustion of the running weft having, in combination, a shuttle-box movable upon the lay at the replenishing side of the loom; weft-detector controlled mechanism which moves said shuttle-box for the purpose of obtaining a fresh supply of weft and for ejection of the depleted weft-carrier; a thread-director; and actuating devices between the thread-director and said shuttle-box which actuate the thread director when the shuttle-box moves, whereby the thread-director catches the weft and delivers it to the cutter.

In witness whereof, I have hereunto signed my name in the presence of two subscribing witnesses.

EUGENE H. BALLOU.
